METHOD OF AND MACHINE FOR GRINDING
TAPERED ROLLERSJohn W. Smith, New Britain, Conn., assignor, by
mesne assignments, to The Timken Roller
Bearing Company, a corporation of OhioApplication February 26, 1923, Serial No. 621,119
Renewed October 28, 1926

21 Claims. (Cl. 51—103)

My invention relates to a centerless grinding method of and machine for grinding tapered rollers such as are used in tapered roller bearings.

In general the object of my invention is to provide a simple and efficient centerless grinding method of and machine for rapidly and economically grinding tapered rollers.

It is a more specific object of my invention to provide a centerless grinding method of and machine for grinding tapered rollers in which blanks to be ground may be continuously fed in at one side of a grinding wheel with their axes at an angle thereto, fed or guided across the grinding surface so as to grind the blanks on a taper, and the finished tapered rollers discharged at the opposite side of the grinding wheel.

In the preferred form of machine for carrying out my invention, a work holder, often termed the regulating member in the centerless grinding art, is mounted adjacent the grinding face of a grinding wheel and the work holder is preferably provided with a helical groove for holding blanks to be ground and causing the latter to be progressed or guided across the face of the grinding wheel. The bottom of the helical groove is formed at an angle to the axis of the work holder, so that the axes of the blanks held in the groove will be presented at an angle to the face of the grinding wheel so as to cause the blanks to be ground on a taper. A work support serves to position the blanks held between the regulating and grinding wheels. The work holder is rotated at a suitable speed relatively to the speed of the grinding wheel, so as to cause the blanks to be rotated and to be ground on a taper by the grinding wheel and the tapered rollers to be successively discharged after being ground.

In the drawing which shows for illustrative purposes only, a preferred form of the invention:

Fig. 1 is a top plan view of a centerless grinding machine embodying features of my invention.

Fig. 2 is a vertical sectional view through the machine shown in Fig. 1.

Fig. 3 is a relatively enlarged, fragmentary, sectional view of a section of a grinding wheel and work holding means with blanks in position to be ground.

In the preferred form shown, a suitable base 5 is provided, on which is mounted the grinding wheel base 6, having the bearing standards 7—7 thereon. The grinding wheel 8 is mounted on a shaft 9 running in suitable bearings in the standards 7—7. A pulley 10 on the shaft 9 serves to drive the grinding wheel as will be readily understood. The base 6, together with the shield or

hood 11, is preferably slidably mounted on the base 5, and a positioning screw 12, coacting with the lug 13 and actuated by the hand wheel 14, serves to position the grinding disk in proper position relatively to the work holder so as to compensate for wear on the wheel and to permit the grinding of blanks of different sizes.

In the present disclosure the base 5 is provided with the work holder standards 15—15 and the work holder 19 between said standards is supported by the shafts 16—17 journalled in said standards. The work holder or regulating member 19 is rotated to feed or guide and rotate the blanks and in the form shown is driven from the main shaft 9 by means of the belt 18. The speed ratio of the work holder and grinding wheel will vary according to conditions.

The work holder itself is preferably in the form of a substantially cylindrical body and a helical groove 20 is so formed in the body 19 that the bottom of the groove lies at an angle to the axis of the cylindrical body in order that tapered rollers may be ground, as will be hereinafter described.

Between the grinding wheel and the work holder 19 may be positioned the work support 22, which is preferably inclined at the top as shown in Fig. 2, so as to cause the blanks to tend to fall away from the wheel. On reference to Fig. 2, it will be seen that a blank such as 23 will be supported in the grinding throat formed by and between the grinding wheel, the work support, and the work holder or regulating member.

A feed chute 25 has been conventionally shown, and a similar conventional discharge chute is designated 26.

The operation is as follows:

The pulley 10 is driven so as to cause the grinding wheel to be rotated at the proper speed and in counter-clockwise direction to cause the grinding surface adjacent the work rest 22 to travel downwardly as viewed in Fig. 2. Through the medium of the belt 18, the work holder or regulating member 19 is rotated at a relatively slow rate in counter-clockwise direction to cause the surface adjacent the work rest 22 to travel upwardly as viewed in Fig. 2. Blanks to be ground are introduced into the feed chute 25 and fed, preferably by gravity, to the work holder where they position themselves in the helical groove 20 and are fed or guided across the face of the grinding wheel by means of the helical ribs or top defining portions of the helical groove. Now, since the bottom of the helical groove is inclined at an angle to the axis of the holder 110

and to the face of the grinding wheel, it will be obvious that each of the blanks will be presented to the grinding wheel with the axes at an angle to the grinding wheel, so that each blank will be ground on a taper. The grinding surface, the helical inclined surface and the work support form a tapered throat or a plurality of such throats progressive longitudinally during rotation of the work holder. The blanks in the helical groove will be fed or guided across the face of the grinding wheel in a path substantially parallel to the grinding face and, due to the rotation of the work holder or regulating member and the grinding wheel, the blanks will be rotated on their own axes and their rotation controlled so as to present the entire surface of the blank to the grinding wheel so that a complete and finished tapered article will be produced. The ground tapered blanks will be discharged into the discharge chute 26 and conveyed to a suitable container.

In the form shown the work holder is provided with two helical grooves. The speed at which the blanks are fed or guided across the face of the grinding wheel will of course depend on the speed of rotation of the work holder and the pitch of the rib thereon and proper speed of feed will of course depend upon conditions and be regulated accordingly.

It will be seen that with the machine herein described, tapered rollers may be very rapidly and economically produced. The machine is substantially automatic, the blanks being fed in at one side and discharged at the other. For rollers having different tapers, it will of course be necessary to substitute work holders having the helical groove at a different angle to the axis of the holder, and for rollers of different thickness it is necessary to adjust the distance between the holder or regulating member and the grinding wheel.

Tapered rollers have been ground, prior to my invention, without the aid of chucks or centers, that is, by the centerless grinding method, on machines having a grinding wheel and a work holder or regulating wheel, together with a work support, all arranged so as to produce a tapered throat. The blanks to be ground are fed into this tapered throat to an extent sufficient to form or finish a tapered surface, after which the tapered roll is withdrawn rearwardly and a new blank inserted.

I believe I am the first to produce tapered rollers by the centerless grinding method where-in blanks may be continuously fed in endwise one after the other at one side of a grinding wheel, fed or guided endwise across the latter, and discharged as finished tapered rollers at the opposite side of the grinding wheel. My new method is continuous, rapid and economical, and the wear on the grinding as well as on the regulating wheel is more uniform than when the intermittent in and out feeding method heretofore mentioned is employed.

The invention has been described specifically in connection with the grinding of tapered rollers, but the principles of the invention are applicable to the grinding of other elongated bodies whether tapered or not.

It is to be noted that one of the wheels, and as specifically shown the regulating wheel, is provided with means to position a work piece axially during grinding; such means preferably is in the form of a rib which may extend spirally or helically so as to cause or permit axial feed-

ing of the work piece in addition to axial positioning thereof.

While I have described in detail a preferred form of my invention, I do not wish to be limited to the form herein shown, for many changes may be made within the scope of the appended claims.

I claim:

1. In a centerless grinding machine, a grinding wheel, a work holder positioned adjacent the face of said grinding wheel and comprising a substantially cylindrical body having a helical groove on the outside thereof for holding a blank to be ground, the bottom of said groove lying at an angle to the axis to the cylindrical body, a work support positioned between the grinding wheel and work holder whereby a blank may be held by the wheel, the work support and work holder, and means for rotating said grinding wheel and said work holder to cause the blank to be fed across the face of the grinding wheel and to be ground to frustro conical shape.

2. In a centerless grinding machine for finishing tapered rollers, a grinding element, means for holding a plurality of roller blanks with their axes pitched at an angle to said grinding element, and means for guiding said plurality of roller blanks endwise across said grinding element, in a path substantially parallel to the grinding element whereby rollers may engage said grinding element at one side and be discharged at the opposite side.

3. In a centerless grinding machine for finishing tapered rollers, a grinding element, rotating means for holding a plurality of roller blanks in engagement with said grinding element in end to end relation with their axes pitched at an angle to said grinding element, and means for rotating said first mentioned means for causing said roller blanks to rotate on their own axes and to cause said roller blanks to be fed across said grinding element in a path substantially parallel to said grinding element.

4. In a centerless grinding machine for finishing tapered rollers, a grinding element, a plurality of supporting means for roller blanks to support the latter in endwise relation and with the axes of said roller blanks at an angle to the grinding element, means for rotating one of said supporting means to cause said roller blanks to be rotated during their passage across said grinding element, and means for guiding roller blanks longitudinally and in succession across said grinding element whereby rollers may be ground and successively discharged at one side of said grinding element.

5. The centerless grinding method of grinding a tapered roller which includes, supporting a roller substantially along elements of a conical surface and in contact with a grinding surface substantially along an element of the same conical surface and causing a relative movement between the roller blank and grinding surface along a path substantially parallel to the grinding surface until the entire roller has passed endwise from one side of the grinding surface to the other, and rotating the roller while in contact with the grinding surface.

6. In a centerless grinding machine for grinding tapered rollers, a grinding wheel, work holding means for engaging a roller blank substantially along elements thereof and holding the roller blank in engagement with said grinding wheel substantially along an element of said roller blank with the axis of said blank pitched at

- an angle to the grinding surface of said grinding wheel, and means for causing a relative movement between the roller blank and said grinding wheel in a path substantially parallel to the 5 grinding surface of said wheel to cause the entire roller to pass from one side of the grinding wheel to the other side thereof.
7. A centerless grinding machine for grinding tapered rollers including a grinding wheel having 10 a relatively wide face, a work holder rotatably mounted adjacent the face of said grinding wheel, said work holder having a helically formed roller supporting surface thereon pitched at an angle to the grinding face of said wheel, work 15 supporting means between said grinding face and work holder, whereby said grinding face and work support and helically formed supporting surface constitute a tapered grinding throat progressive longitudinally from one side of said 20 grinding face to the other during rotation of said work holder, and means for guiding a roller blank held in said grinding throat from one side of said grinding face to the other whereby rollers may be entered at one side of said grinding face and discharged after being ground at the opposite side thereof.
8. A centerless grinding machine including a 30 grinding wheel, a rotatable drum having a helical groove therein for supporting a roller with the axis pitched at an angle to the grinding face of the wheel, a second supporting means for the roller in said helical groove, and means for rotating said drum for feeding the roller in said helical groove across the grinding face of said 35 grinding member for grinding a tapered surface thereon.
9. A centerless grinding machine including a 40 grinding wheel, means for supporting a blank to be ground with the axis of the blank pitched at an angle to the grinding face of said grinding wheel, whereby a tapered surface will be ground on the blank, said means including a rotatable drum having a helical groove therein for receiving blanks to be ground and feeding the same 45 across the face of said grinding wheel.
10. In a centerless grinding machine, a grinding wheel, a work holder positioned adjacent the face of said grinding wheel and comprising a substantially cylindrical body having a helical 50 groove on the outside thereof for positioning a blank to be ground, a work support for supporting a blank positioned between the bottom of said groove and the face of said wheel, the bottom of said groove being formed to engage a blank 55 along a substantially straight line whereby a blank positioned between the bottom of said groove and the face of said grinding wheel and said work support will be definitely held against rotation except about the axis of the blank, means for rotating said grinding wheel and said work holder at different surface speeds whereby a blank will be ground by said grinding wheel and its rotation about its axis controlled by the rotation of said work holder, and whereby movement of the blank 60 across the face of said grinding wheel will be positively controlled by an edge of said groove.
11. In a centerless grinder, a rotatable grinding wheel, a work holder for positioning a blank between the grinding face of said wheel and said 65 work holder, said work holder being formed to prevent rotation of the blank except about its axis, said work holder being movable in a direction opposite to the direction of movement of the grinding face of said wheel and at a different speed, and helical means 70 including a work rest, a work regulating wheel 75
- for positively controlling movement of a blank across the grinding face of said wheel while being held between said work holder and said grinding wheel, said work holder serving to control the rotation of a blank while being positioned as 80 aforesaid.
12. In a centerless grinder, a grinding wheel, a work holder and a work support, said members having surfaces to engage a blank to be ground and to prevent rotation of the blank except about its own axis, means for moving the grinding surface of said grinding wheel and said work holder in opposite directions and at different speeds whereby rotation of the blank about its own axis will be controlled, and helical means for positively controlling the passage of a blank positioned by said grinding wheel and work holder and work support, across the grinding surface of said wheel.
13. A precision grinding machine of the centerless type comprising a bed, a work support rigidly carried thereby, a grinding wheel mounted on the bed adjacent the support for rotation in the direction of the support, and a regulating wheel supported by the bed at the opposite side of the work support having its surface adjacent the support driven upwardly with respect thereto, said regulating wheel having a face portion for lateral engagement with an elongated work piece to control the rotation thereof and having a helically extending rib projecting from said face and adapted terminally to engage the work pieces to insure positive axially feeding movement of said pieces along the work support.
14. A machine for centerless grinding of 110 tapered articles including a work support, a grinding wheel adjacent the work support operable at a high or grinding speed with its operative portion moving in a direction toward the work support, and a regulating member disposed 115 adjacent the support in opposition to the grinding wheel with its operative surface movable upwardly as respects the support and at a slow rate of speed to frictionally engage and control the rotation of work pieces on the support, said 120 parts together forming a work receiving throat and said regulating member being formed with a transversely tilted helical path providing a series of work receiving recesses adapted to support a plurality of work pieces in opposition 125 to the operative portion of the grinding wheel whereby rotation of the work controlling member will rotate the work pieces and cause a transverse shifting of the effective portions of the paths to feed the work pieces axially along the 130 support and transversely of the grinding member substantially as described.
15. A machine for producing non-cylindrical elongated work including a rigid work support for a plurality of work pieces, a grinding member 135 at one side of the support and regulating means in opposition to the grinding member having a plurality of portions for line contact with the distant sides of individual work pieces to present the grinding wheel sides thereof in a continuous line parallel to the face of the grinding wheel when the work pieces are of the prescribed taper, said regulating wheel having distant portions for rotating the work pieces and for axially advancing the work pieces during rotation, while maintaining their prescribed relation to the grinding 140 wheel.
16. A machine for the multiple production of 145 tapered articles such as rolls for roller bearings including a work rest, a work regulating wheel 150

- for supporting and controlling the position and rotation of the work during grinding and an opposed grinding wheel disposed in cooperative relation to said parts for simultaneous grinding of a plurality of rolls supported thereby, one of the two first named parts having a plurality of tilted work receiving recesses formed therein corresponding in shape to that of the work pieces whereby a plurality of similar work pieces will be simultaneously supported by said member for corresponding engagement by the grinding wheel. 10
17. A machine for the multiple production of tapered articles such as rolls for roller bearings including a work rest and a work regulating wheel for supporting and controlling the position and rotation of the work during grinding and an opposed grinding wheel disposed in cooperative relation to said parts for simultaneous grinding of a plurality of rolls supported thereby, one of the two first named parts having a plurality of tilted work receiving recesses formed therein corresponding in shape to that of the work pieces whereby a plurality of similar work pieces will be simultaneously supported by said member for corresponding engagement by the grinding wheel, 15 and one of the two first named members have portions extending adjacent the tapered work receiving seats for terminal engagement with the individual work pieces therein to determine the axial position of said individual work pieces with respect to their seats and thus the finished diameter thereof as produced by the grinding wheel. 20
18. A grinding machine of the centerless type including a bed, a work support carried thereby, a rotatable grinding wheel at one side of and adjacent the work support, a rotatable regulating wheel on the opposite side of said work support, said regulating wheel having a surface opposed to the grinding wheel surface and pitched at an angle thereto, whereby a tapered work piece may be supported by said work support and in contact with the grinding face of said grinding wheel and the said surface of said regulating wheel pitched at an angle to said grinding wheel surface, and means on said regu- 25
20. A grinding machine of the centerless type including a bed, a work support carried thereby, a rotatable grinding wheel at one side of and adjacent said support, and a rotatable regulating wheel on the opposite side of said support, said regulating wheel having a work engaging path to engage the side of a tapered work piece and hold the opposite side thereof in contact with the grinding face of said grinding wheel and control the rotation of the tapered work piece during grinding thereof, said regulating wheel having means to position a tapered work piece 105 axially during the grinding thereof. 25
21. A grinding machine of the centerless type including a bed, a work support carried thereby, a rotatable grinding wheel at one side of and adjacent said support, a rotatable regulating wheel on the opposite side of said support, said wheels having opposed faces positioned at an angle to each other whereby said opposed faces and said work support form a tapered grinding throat for the reception of a tapered work piece 110 to be ground, one of said wheels having means to engage and axially position a tapered work piece during grinding thereof. 115

- for supporting and controlling the position and rotation of the work during grinding and an opposed grinding wheel disposed in cooperative relation to said parts for simultaneous grinding of a plurality of rolls supported thereby, one of the two first named parts having a plurality of tilted work receiving recesses formed therein corresponding in shape to that of the work pieces whereby a plurality of similar work pieces will be simultaneously supported by said member for corresponding engagement by the grinding wheel.
17. A machine for the multiple production of tapered articles such as rolls for roller bearings including a work rest and a work regulating wheel for supporting and controlling the position and rotation of the work during grinding and an opposed grinding wheel disposed in cooperative relation to said parts for simultaneous grinding of a plurality of rolls supported thereby, one of the two first named parts having a plurality of tilted work receiving recesses formed therein corresponding in shape to that of the work pieces whereby a plurality of similar work pieces will be simultaneously supported by said member for corresponding engagement by the grinding wheel,
- 25 and one of the two first named members have portions extending adjacent the tapered work receiving seats for terminal engagement with the individual work pieces therein to determine the axial position of said individual work pieces with respect to their seats and thus the finished diameter thereof as produced by the grinding wheel.
18. A grinding machine of the centerless type including a bed, a work support carried thereby, a rotatable grinding wheel at one side of and adjacent the work support, a rotatable regulating wheel on the opposite side of said work support, said regulating wheel having a surface opposed to the grinding wheel surface and pitched at an angle thereto, whereby a tapered work piece may be supported by said work support and in contact with the grinding face of said grinding wheel and the said surface of said regulating wheel pitched at an angle to said grinding wheel surface, and means on said regu-
- 20 lating wheel for axially positioning a tapered work piece relatively to said pitched surface.
19. A grinding machine of the centerless type including a bed, a work support carried thereby, a rotatable grinding wheel at one side of and adjacent the work support, a rotatable regulating wheel on the opposite side of said work support, said regulating wheel having a surface opposed to the grinding wheel surface and pitched at an angle thereto, whereby a tapered work piece may be supported by said work support and in contact with the grinding face of said grinding wheel and the said surface of said regulating wheel pitched at an angle to said grinding wheel surface, and means on said regulating wheel for axially positioning a tapered work piece relatively to said pitched surface and feeding the work piece axially.
- 25 20. A grinding machine of the centerless type including a bed, a work support carried thereby, a rotatable grinding wheel at one side of and adjacent said support, and a rotatable regulating wheel on the opposite side of said support, said regulating wheel having a work engaging path to engage the side of a tapered work piece and hold the opposite side thereof in contact with the grinding face of said grinding wheel and control the rotation of the tapered work piece during grinding thereof, said regulating wheel having means to position a tapered work piece axially during the grinding thereof.
- 25 21. A grinding machine of the centerless type including a bed, a work support carried thereby, a rotatable grinding wheel at one side of and adjacent said support, a rotatable regulating wheel on the opposite side of said support, said wheels having opposed faces positioned at an angle to each other whereby said opposed faces and said work support form a tapered grinding throat for the reception of a tapered work piece to be ground, one of said wheels having means to engage and axially position a tapered work piece during grinding thereof.
